UNITED STATES PATENT OFFICE.

GEORGE T. STEVENS, OF AUCKLAND, NEW ZEALAND.

SHOE-FASTENING.

SPECIFICATION forming part of Letters Patent No. 395,088, dated December 25, 1888.

Application filed May 1, 1888. Serial No. 272,448. (No model.)

To all whom it may concern:

Be it known that I, GEORGE TRACY STEVENS, of Auckland, New Zealand, have invented a new and useful Improvement in 5 Shoes and Lacers Therefor, of which the following is a full, clear, and exact description.

My invention relates to an improvement in shoes and lacers for the same, and has for its object to provide a means whereby a shoe 10 will be stiffened at the top to sustain the strain exerted thereon when the laces are drawn, and also to provide a means whereby the shoe may be conveniently and readily expanded at the top for the insertion of the foot, 15 and expeditiously laced by simply drawing upon the projecting extremities of the strings or laces.

The invention consists in the construction and combination of the several parts, as will 20 be hereinafter fully set forth, and pointed out in the claims.

Reference is to be had to the accompanying drawings, forming a part of this specification, in which similar letters of reference indicate 25 corresponding parts in both the figures.

Figure 1 is a perspective view of a laced shoe, partly in section; and Fig. 2 is an elevation of the abutting front edges of the upper, illustrating the application of the lace thereto.

30 In carrying out the invention in the front opposing edges, *a*, of the upper *A* a strip, *B*, of metal, whalebone, stiff rubber, or similar material is inserted between the several strips of leather or the leather and lining, as best 35 shown in Fig. 1, which stay is secured in any suitable or approved manner, and provided with apertures adapted to receive the eyelets *b*. The purpose of this stay is to furnish 40 a brace, whereby the operator by grasping the same may readily force the contiguous front edges of the upper in opposite directions for the convenient admission of the foot; and a further object of the stay is to provide a rigid surface, through which the 45 laces may be drawn to effectually close the upper over the foot at one operation. To accomplish this result, laces *d* *d'* and *d*² *d'*² are usually employed, two for each side being inserted in the eyelets of the shoe, essentially 50 in the following manner.

Supposing the shoe to have eight eyelets *b*

upon each side of the front opening of the upper and an enlarged upper eyelet, *b'* *b*², one end of the lace *d* is passed from the outside downward through the opening *b'* within 55 the shoe, out through the lower eyelet in the side *D*, across the opening through the similar and aligning eyelet in the side *D'*, upward through the second eyelet in the same side, from thence inward through the aligning eyelet in the side *D*, and further upward within 60 the shoe, out through the opening *b'* in the said side. Thus the two ends of lace *d* project out in parallel line through the same upper opening—namely, that in the side *D*. A 65 group of four eyelets are now skipped and the second lace, *d'*, is passed through the aforesaid opening *b'* in the side *D* and through the third group of four eyelets in similar manner to the aforesaid lace *d*. This having been 70 accomplished, the ends of the laces *d* and *d'* are united in any approved manner, as best shown in Fig. 1. One end of the lace *d*² is now projected downward through the opening *b*² in the side *D'*; up through the third 75 eyelet from the bottom on said side, across the front, down through the horizontal aligning eyelet in the side *D*, vertically upward and outward through the next upper eyelet in 80 said side *D*, and inward through the horizontally-aligning eyelet in the opposite side, and thence out through the upper opening, *b*². The lace *d*² is passed in a similar manner through 85 the upper opening, *b*², and through the upper group of four eyelets in the stiffening, whereupon the projecting ends of the laces *d*² and *d'*² are also united.

In operation the stayed portions of the shoe are grasped with the hands, and the sides *D* and *D'* carried in opposite directions. As the 90 sides are thus separated, the laces run freely through the eyelets, permitting the movement to be accomplished with ease. The foot may now be readily inserted. To close the upper over the foot, the opposite projecting ends of 95 the laces are pulled upward and preferably outward, which immediately brings the opposing edges of the upper essentially in contact by reason of the stiffening in the upper portion of the shoe, which permits direct and 100 even tension to be exerted upon all the laces. The end of the laces may now be tied or se-

cured upon a cleat, or fastened in any approved manner.

I do not confine myself to four laces, as any desired number may be employed without departing from the spirit of the invention.

Having thus described my invention, what I claim as new, and desire to secure by Letters Patent, is—

1. The combination, with an eyeleted shoe having rigid stays B upon opposite sides of the front opening above the instep, and having apertures in line with the shoe-apertures to receive the eyelets, of laces passing back and forth through the said eyelets, substantially as set forth.

2. The combination, with an eyeleted shoe, and rigid stays secured at the top of the upper upon opposite sides of the front opening, of in-

dependent laces projected outward through the upper horizontally-aligned eyelets, each of said laces passing through separate groups of the remaining eyelets, substantially as shown and described.

3. The combination, with an eyeleted shoe and rigid stays secured at the top of the uppers upon opposite sides of the front opening, of independent laces passing through alternate groups of eyelets and projected outward through the horizontal aligning top eyelets, each set of laces having their ends united, substantially as shown and described.
